UNITED STATES PATENT OFFICE.

MARYA POLTORAK, OF NICETOWN, PENNSYLVANIA.

DESIGN FOR AN INKSTAND.

42,060.

Specification for Design.

Patented Dec. 26, 1911.

Application filed May 10, 1911. Serial No. 626,374. Term of patent 14 years.

To all whom it may concern:

Be it known that I, MARYA POLTORAK, a subject of the Emperor of Austria, residing at Nicetown, in the county of Philadelphia and State of Pennsylvania, have invented a certain new, original, and ornamental Design for an Inkstand, of which the following is the specification, reference being had to the accompanying drawing, forming a part thereof.

The figure is a perspective view of the inkstand, illustrating my new design.

I claim:

The ornamental design for an inkstand, as shown.

MARYA ^{her} X POLTORAK.
